UNITED STATES PATENT OFFICE.

THEODORE CHANOCK, OF CHICAGO, ILLINOIS.

DESIGN FOR A LAMP BASE.

Application filed January 29, 1926. Serial No. 16,326. Term of patent 3½ years.

To all whom it may concern:

Be it known that I, THEODORE CHANOCK, a citizen of the United States, residing at Chicago, in the county of Cook and State of Illinois, have invented a new, original, and ornamental Design for a Lamp Base, of which the following specification, reference being had to the accompanying drawings, forms a part thereof.

Figure 1 is a fragmentary top plan view of a lamp base, the balance of the ornamentation within the dotted outline being a repetition of the fragment shown; and Figure 2 is a side elevational view of a lamp base embodying my design.

I claim:

The ornamental design for a lamp base substantially as shown.

THEODORE CHANOCK.
